UNITED STATES PATENT OFFICE.

JACOB BOLANDER, OF TORONTO, ONTARIO, CANADA.

BAG-HOLDER.

1,269,577.

Specification of Letters Patent. Patented June 18, 1918.

Application filed November 26, 1917. Serial No. 204,065.

To all whom it may concern:

Be it known that I, JACOB BOLANDER, of the city of Toronto, in the county of York, in the Province of Ontario, in the Dominion 5 of Canada, have invented certain new and useful Improvements in Bag-Holders, and do hereby declare that the following is a full, clear, and exact description of same.

This invention relates to adjustable devices for the supporting of bags in an open condition to facilitate the filling of such bags, being particularly adaptable for such purposes as mail-sorting, grain-bagging and like purposes, and having as an object to 10 provide a readily-operable and adjustable device of simple construction which will effect the supporting of a bag in a very secure manner, whereby liability of the said bag to slip, or be accidentally displaced, 15 from the support will be materially obviated; an important object also being to arrange resilient gripping members in such relation to bag-supporting arms, with which they coöperate, that the pressure of the said 20 gripping members may be concentrated at certain desirable points, upon a bag being supported by the device, to secure great efficiency in the said gripping operation together with certain other advantages which 25 will be hereinafter pointed out.

Further objects subsidiary to or resulting from the above-mentioned main objects, or from the construction of the invention as it may be carried into effect, will become apparent as the invention is hereinafter further disclosed.

In carrying my said invention into effect I may provide, as an example, the novel construction and arrangement of parts 40 whereby a frame or head is, preferably, slidably arranged and vertically adjustable upon a vertical support, said frame having hinged thereto, and disposed upon either side thereof, a pair of outwardly-extending 45 bag-supporting arms which may swing upon their hinges, over respective quadrants forming part of the base of said frame, one or both of which quadrants may be provided with teeth with which suitable interlocking means, carried by the arm or 50 arms, may detachably engage to determine the adjustment of the said arms with respect to one another; and it is preferred that a link connection should be provided between, 55 and co-acting with, the said arms whereby angular adjustment of one of the said arms

will be accompanied by the synchronous adjustment of the other of said arms, but in an opposite direction thereto, as will be readily understood. The outer parts of the 60 arms, that is, the parts which are intended to actually engage with the bag, are preferably somewhat raised above the plane of the inner parts of the said arms in proximity to the quadrants, whereby the rim of 65 the bag may be folded thereover so that the body of the bag will depend between the arms, and gripping members secured to the said arms adjacent to said quadrants and adapted to swing vertically out of operative 70 position, may be arranged in such manner that, when in their securing position, the outer ends of the said gripping members are secured in contact with that part of a bag contiguous to the outer ends 75 of the supporting arms by suitable securing means, such as clips, against resilience in the said members, the said members also impinging upon the said bag at points substantially removed from the extremities of 80 the said arms, whereby the resilient forces, in the said arms, are concentrated at these points, and also clearance provided between the gripping members and the supporting arms, intermediate of the said points of 85 resilient contact therebetween and the points of contact at the extremities thereof, all of which is more particularly described and ascertained hereinafter, having reference to the example illustrated in the accompanying 90 drawings, in which:

Figure 1 is a perspective view of the frame, bag-supporting arms, grippers and parts associated therewith.

Fig. 2 is a broken plan view of the same, 95 and

Fig. 3 is a broken elevation of a complete device, with a bag secured in position and a hopper shown which may be used in connection therewith where desirable. 100

Similar characters of reference indicate similar parts in the several figures of the drawings.

1 is a vertical support and 2 a frame or head vertically adjustable on the said support 1, adapted to be locked in any such vertically-adjusted position by means of the thumb screw 3, the form of frame shown in the drawings being characterized by quadrants 2^a and 2^b, one of which is serrated or toothed near its periphery, a pair of radial hinge housings 2^c and 2^d and a pivot lug 2^e.

extending upwardly from the base of said frame intermediate of the said quadrants 2^a and 2^b. Hingedly mounted on pins 4 and 5 respectively through the hinge housings 2^c and 2^d are outwardly extending arms 6 and 7 hereinafter called the bag-supporting arms, vertically offset intermediate of their length, whereby shoulders 6^a and 7^a are provided, and preferably substantially offset laterally in proximity to the said shoulders, as will be readily understood from an examination of Fig. 2 of the drawings, that is to say, the said bag-supporting arms have each a lateral S bend therein whereby the distance between the said arms is substantially increased intermediate of their length. It will be seen that the said bag-supporting arms 6 and 7 are capable of swinging over the quadrants 2^a and 2^b respectively, and in order to synchronize the movement of the said arms toward or away from one another, a link connection therebetween may be provided comprising a pivoted lever 8 mounted intermediate of its length upon the pivot lug 2^e already referred to, and having one end connected by a link 9 to the arm 6 and the other end by a further link 10 to the arm 7. The said lever 8 is preferably pivoted at a point somewhat nearer the end carrying the innermost link 10 in order to secure an equal movement of the two arms.

It will be seen that the arms, as constructed, permit a bag to be supported therebetween while the rim of the bag may be folded thereover to engage with the said arms in the manner as particularly indicated in Fig. 3 of the drawings, so that if a bag be so supported by the said arms and the arms be distended as far as the rim of the bag will permit, then an appreciable downward force in the body of the bag would be required to remove the same from the said supporting arms, due to the binding effect of the folded rim thereon.

In order to insure a very efficient gripping of the bag upon the arms, grippers 11 and 12 are provided, in the form of resilient metal strips hinged at 13 and 14 to the inner parts of the said arms 6 and 7 respectively, the outer ends of the said grippers having clips 15 and 16 mounted thereon to engage with the outer ends of the said bag-supporting arms, when the grippers 11 and 12 are brought into operative position. It will be seen from an examination of Fig. 2 of the drawings that the laterally offset part of each arm passes somewhat beyond a plane between the hinge of the respective gripper and the end of the arm, with which the clip carried by the said gripper engages, so that, when bringing the clips into engagement with the arms, the said grippers will first contact intermediate of their length with the laterally offset parts (forming stops for said grippers) of the said arms, whereby the

completion of the closing of the grippers against the arms must be effected against the lateral resilience of the said grippers; and the arms may be so shaped that when the grippers are so secured in their operative position, clearance is provided, between the grippers and the respective arms, intermediate of the said points of resilient contact therebetween and the points of contact at the extremities thereof, these features being all illustrated in the said Fig. 2. The hinged nature of the grippers permits them to be swung upwardly so that they do not interfere with the adjusting of the rim of the bag upon the gripper arms prior to bringing the said grippers into operation.

In Fig. 3 of the drawings a hopper 17 is shown which may be very conveniently used with the device described, said hopper being carried by a ring 18 revolvably mounted, upon the support 1, whereby the hopper may be swung out of position during the adjustment of the arms and grippers.

By the use of this invention, a bag may be supported in such manner that the frictional resistance, due to the folding of the rim thereof over supporting members, is employed, to effect the securing of the bag against displacement, in combination with the concentration of resilient force at certain desirable points, together with the securing, by clips, of the bag at the extremities of the supporting members; and the relative arrangement of the arms and their respective grippers, whereby clearance is provided therebetween throughout part of their length, while contributing to the concentration of forces already described, also permits bags having heavy seams therein to be used with the device without loss of efficiency so far as the mechanical operation of the device is concerned.

This invention may be developed within the scope of the following claims without departing from the essential features of the said invention, and it is desired that the specification and drawings be read as being merely illustrative and not in a limiting sense, except as required by the prior art.

What I claim as my invention is:

1. In a bag holder, a pair of bag-supporting arms provided with upwardly offset portions over which the rim of a bag may be folded, grippers secured at their inner ends to said arms, said grippers, when operative, extending along the outer surfaces of the upwardly offset portions of said arms, and locking means carried at the free ends of the grippers to engage the arms.

2. In a bag holder, a pair of bag-supporting arms provided with upwardly offset portions over which the rim of a bag may be folded, and grippers hingedly secured at their inner ends to said arms, the outer ends of said grippers being adapted to engage

the upwardly extending offset portions of said arms to bind the folded rim of the bag thereon.

3. In a bag holder, a laterally offset bag-
5 supporting arm, a laterally elongated gripper secured at one end to said arm, and means to detachably secure the free end of said gripper to said arm, whereby when the gripper is attached at both ends to the arm
10 the intermediate portion thereof will impinge against the lateral offset in the arm and the closing of said gripper is effected against the resilience thereof.

4. In a bag holder, a bag supporting arm,

an elongated, resilient gripper, swingably 15 mounted on said bag holder to move laterally with respect to said arm, said supporting arm forming a stop to contact with said gripper intermediate of its length, when said gripper is partly closed on said arm, whereby the full closing of said gripper will be effected against the resilience thereof.

Signed at the city of Toronto, in the county of York, in the Province of Ontario, in the Dominion of Canada, this 20th day 20
25 of November, 1917.

JACOB BOLANDER.
